UNITED STATES PATENT OFFICE.

RALPH B. PILLSBURY, OF BENTON STATION, MAINE.

COMBINED CONTAINER AND DISPENSER.

Application filed April 13, 1925, Serial No. 22,843. Renewed March 24, 1927.

My invention relates to improvements in combined containers and dispensers, of the general type which has been heretofore devised for boxing matches and for constituting a match safe, and while the present invention could be constructed of such size for this use, it is intended primarily for use in connection with poultry raising, for containing and shipping feeds, regulators, grit and kindred materials, the construction being such that the purchaser of the device may quickly and easily adjust the same to form a self-feeder.

The primary object of the invention is to provide a new and improved construction for the lower end portion of the inner unit of the device, including a back wall having a free lower end, a false bottom connected to said lower wall and resting slidably on a lower end wall of the inner unit, a short front wall rising from the false bottom, and a pair of side cheeks extending rearwardly from said front wall and formed with notches to be engaged by the lower end of the outer unit or sheath of the device, when said lower end of the back wall, said false bottom, said front wall and said side cheeks are forced rearwardly after upward sliding of the sheath. Thus, a device is produced which effectively feeds the material contained therein toward the open portion thereof, to be readily accessible to the poultry, or to the human fingers, if the device is to be used for matches or the like.

With the foregoing in view, the invention resides in the novel subject matter hereinafter described and claimed, the description being supplemented by the accompanying drawing.

Figure 1 is a perspective view of the invention in dispensing position.

Figure 2 is a vertical sectional view through the device in the condition which it assumes before it is opened for use.

Figure 3 is a vertical sectional view through the device in the condition shown in Fig. 1.

Figure 4 is a horizontal sectional view on line 4-4 of Fig. 3.

Figure 5 is a perspective view of the inner unit of the device.

Figure 6 is a perspective of the outer unit or sheath.

In the drawings above briefly described, I designates an inner unit of the combined

container and dispenser, and S indicates the outer unit or sheath.

The inner unit I comprises a pair of parallel vertical side walls 1, upper and lower end walls 2 and 3 connecting said side walls, and a vertical back wall 4 connected with the end wall 2 and having its upper portion connected to the side walls 1, as far as the points 5, but having its lower portion free of connection with said side walls and also free of connection with the lower end wall 3. This free lower end of the back wall is indicated at 6, and from it a false bottom 7 extends forwardly, said false bottom resting slidably upon the lower end wall 3. Rising from the front end of this false bottom 7, is a short front wall 8, and a pair of side cheeks 9 project rearwardly from this front wall and slidably engage the inner sides of the side walls 1, the upper edges of said side cheeks having notches 10 which are spaced rearwardly from the front wall 8 and may well be located about midway of the width of said cheeks.

The outer unit or sheath S is of conventional form, but the lower end of its front wall 11, is preferably formed with a pair of notches 12. Normally, the sheath S entirely surrounds the inner section I and covers all parts of the latter except its end walls 2 and 3, so that a tight package is provided to contain any desired substance or articles. When the sheath S is slid upwardly however, as shown in Figs. 1 and 3, the free lower end 6 of the back wall 4, the false bottom 7, the front wall 8, and the side cheeks 9 may be forced forwardly to position the notches 10 under the notches 12. Then, when the sheath S is downwardly slid, the portion of its front wall 11 at the upper ends of the notches 12, seat in said notches 10 and hold the lower portion of the container in the operative position shown in Figs. 1, 3 and 4. At the same time, the notches 12 receive portions of the side cheeks 9 and hold the latter against possible lateral displacement.

It will be seen from the foregoing that a unique device has been provided, which may be easily and inexpensively manufactured from any desired sheet material and when the device is in its dispensing position, ready access is permitted to its contents, and the free lower end 6 of the back wall 4 which then declines forwardly, serves to direct such

contents toward the open dispensing portion of the device.

Excellent results have been obtained from the details disclosed and they are therefore 5 preferably followed. However, within the scope of the invention as claimed, modifications may of course be made.

I claim:

- 10 1. In a combined container and dispenser, an inner unit comprising parallel vertical side walls, upper and lower end walls connecting said side walls, a back wall connected with the upper portions of said side walls and the upper end wall but free of connection with the lower portions of said side walls and the lower end wall, a false bottom connected to the lower end of said back wall and resting slidably on said lower end wall, a short front wall rising from said false bottom, and side cheeks extending rearward-

- 20

ly from said front wall in sliding engagement with said side walls, the upper edges of said cheeks having notches spaced rearwardly from said front wall; and an outer unit or sheath slidably surrounding said 25 inner unit, said sheath being upwardly movable to permit forward shifting of the aforesaid front wall, side cheeks, false bottom and lower portion of the back wall, the lower end of the front of said sheath being then 30 adapted for seating in the notches of said side cheeks.

2. A structure as specified in claim 1; said lower end of the sheath front having notches to receive the upper edges of said 35 side cheeks to prevent lateral shifting thereof.

In testimony whereof I have hereunto affixed my signature.

RALPH B. PILLSBURY.
